W. O. KIDWELL

WASHER AND DRIER

Filed June 30, 1924

INVENTOR,
William O. Kidwell,
By Joseph A. Mutterer
Attorney.

UNITED STATES PATENT OFFICE.

WILLIAM O. KIDWELL, OF INDIANAPOLIS, INDIANA.

WASHER AND DRIER.

Application filed June 30, 1924. Serial No. 723,217.

To all whom it may concern:

Be it known that I, WILLIAM O. KIDWELL, a citizen of the United States, residing at Indianapolis, in the county of Marion and State of Indiana, have invented new and useful Improvements in Washers and Driers, of which the following is a specification.

My invention relates to means of washing and then drying clothes sufficiently for hanging on the line or immediate ironing, and the primary object of my invention is to thoroughly agitate the clothes and force water in and out of them, and upon completion of the washing process, to press the water out of the clothes without having to remove them from the washer or otherwise handle them as has heretofore been necessary with the customary wringer. Further objects are to avoid damage to the clothes and to prevent breakage of buttons or mashing of hooks in either the washing or drying processes, and I accomplish these and such other objects as may become apparent in the following description by the means as illustrated in the accompanying drawing, in which—

Fig. 1 is a side elevation of my washer and drier with fragments of the outer housing, a section of the crankshaft bracket, and a fragment of the clothes-cylinder removed; Fig. 2, a top plan view of the same, with one door partially opened and a fragment of it removed to more fully disclose the relative position of the clothes-cylinder; Fig. 3, an end elevation of the washer and drier with the major portion of the outer housing removed and a vertical section taken through the clothes-cylinder, and showing the rack bar in position and the presser plate partially lifted, a portion of the presser plate, clothes-rack, and guide bars being removed to show their relative positions with the rack bar; Fig. 4, a detail view of the rack bar to indicate the method of attaching it to and detaching it from the presser plate; Fig. 5, a horizontal section through the clothes-cylinder on the line 5—5 in Fig. 1; Fig. 6, a fragmentary detail to indicate the method of holding the clothes rack above the presser plate; and Fig. 7, a detail of the dog arrangement to prevent the clothes from dropping back into the water after being dried; and Fig. 8, a side

elevation of a modification of a clothes-cylinder shown as formed of annular rods 55 supported by outside vertical rods.

Like characters of reference, indicate like parts throughout the several views.

I form a housing 6 of such proportions as to permit a clothes-cylinder 7 to be inserted within the housing, pivotally secured therein to the housing walls by the trunnions 8 and 9, whereby the clothes-cylinder may be completely rotated about the axes of the trunnions without contacting 65 the housing walls. The housing 6 is adapted to hold water and is supported by the legs 10.

The clothes-cylinder 7 here shown as a perforated cylinder may be made of any 70 reticulated material such as interwoven rods or wire, to permit the free inflow and outflow of water between the housing 6 and the clothes-cylinder 7, and still retain clothes within the clothes-cylinder. A bottom plate 11, likewise perforate or reticulate is permanently secured to the clothes-cylinder 7 and centrally and vertically supports the rack-bar guide composed of the two separated semi-circular guide bars 12, 80 a cross-section through which is to be seen in Fig. 5. The guide bars 12 project above the top of the clothes-cylinder substantially to the under sides of the housing enclosing doors 13, but of such length as will permit 85 clearance of the ends of the bars 12 and the housing 6 as the clothes-cylinder is completely revolved.

To retain the clothes within the clothes-cylinder 7 upon turning the cylinder, I 90 fit a top lid 14 over the cylinder 7 which is there secured by means of the spring catches 15 engaging over the rolled projecting rim 16 of the lid. The lid 14 is provided with a central hole as to permit the 95 guide bars 12 to extend therethrough and be supported thereby.

I mount the brackets 17 and 21 on the housing 6 to project upwardly to receive the crankshaft 18 and the guideshift 19, both 100 extending transversely across and above the housing 6, such that the doors 13 may slide and be at a substantial distance thereunder. The doors 13 are slidably retained on the housing 6 by means of the cleats 20 above 105 and below the doors so that considerable up-

ward pressure from the under side of the doors will not displace them.

On the end of the crankshaft 18 projecting outwardly beyond the bracket 17 is secured the hand-crank 22, and on the same side of the bracket 17, the dog wheel 23 is secured to the crankshaft so as to contact the bracket 17 by its side face. A dog 43 is pivotally retained on the end of the guide shaft 19 so as to engage with the dog wheel 23 as in Fig. 7, when desired to arrest the clockwise rotation of the crankshaft 18. On the opposite end of the crankshaft 18 is secured a drive pulley 24 so that the crankshaft may be revolved by power such as a belt driving electric motor or gas engine in place of being hand operated by the crank 22. Between the pulley 24 and the bracket 21, I secure the driving gear 25 to the crankshaft 18, and between the two brackets 17 and 21, I rigidly mount the rack-bar gear 26 on the crankshaft 18, the relative positions of the gears 25 and 26 and the brackets 17 and 21 being such that by sliding the crankshaft 18 endwise to the left as in Fig. 3, through the brackets 17 and 21, the rack-bar gear 26 engages with rack-bar 27 and the drive gear 25 is disengaged and held out of mesh away from the intermediate gear 28 mounted on the side of the housing 6 which meshes permanently with the clothes-cylinder gear 29 secured to the cylinder trunnion 9 which projects through to the outside of the housing. This position of the crankshaft as described is maintained by means of the collar 30 secured to the crankshaft 18 being engaged by the spring latch 31. By sliding the crankshaft to the right, (Fig. 3) the latch 31 is sprung down, the collar 30 slipped over it and held by it so as to retain the collar 30 in contact with the bracket 17, in which position of the crankshaft, the gear 26 is out of mesh with the rack-bar 27 and the gear 25 is in mesh with the gear 28, such that in this latter position of the crankshaft 18, the shaft may be turned to cause a corresponding rotation of the clothes-cylinder 7.

A circular presser plate 32 is normally held slightly above the bottom plate 11 and is formed with semi-circular sections removed about its center so as to slide freely up and down the two guide bars 12 as they extend through these removed sections, the presser plate 32 being so formed as to have in effect an integral tie extending between the space arising by the separated positions of the guide-bars 12. A circular clothes-rack 33 has a complete circular section removed from its center so as to permit its being dropped freely about the two guide-bars 12 so as to rest normally upon the inwardly projecting lugs 34, more clearly indicated in Fig. 6, so positioned as to cause a space to intervene between the clothes-

rack 33 and the presser plate 32. The presser plate 32 is reduced in diameter so as to pass the lugs 34 as the plate 32 may be raised and both the clothes-rack 33 and the presser plate 32 are perforate or reticulate members to permit the passage of water but not of clothes therethrough.

The rack-bar 27 is inserted from the top through a hole 35 formed half in one door 13 and half in the other door 13, see Fig. 2, and is entered into the space between the two guide-bars 12. The lower end of the rack-bar 27 is provided with a restricted neck 36 to which is appended a locking foot 37 adapted to pass closely through the slot 38 in the presser-plate 32 as in Fig. 4. By turning the rack-bar 27, the foot 37 is turned crosswise of the slot 38 as indicated by the dotted lines in Fig. 4, and so secured by contacting the underside of the presser plate, at the same time presenting the tooth side of the rack-bar 27 within the space left open between the two guide bars 12, and also bringing the tooth side of the rack-bar 27 to mesh with the gear 26. As the rack-bar 27 fits rather loosely within the guide-bars 12, it is necessary to provide means of maintaining the rack-bar in proper contact with the gear 26.

Such means, I provide by hinging the roller bracket 39 on the guide-shaft 19. The roller bracket 39 is provided with downwardly depending flanges to support the roller 40 which bears against the back side of the rack-bar 27 as in Figs. 1 and 2, and is further provided with the arms 41 to extend past the rack-bar to prevent its side displacement and to engage by downwardly turned ends on and partially around the crankshaft 18. The roller bracket may be swung up and back out of the way as indicated by the dotted lines in Fig. 1 when it is desired to remove or replace the rack-bar.

To operate my washer and drier, the rack-bar 27 is removed by lifting the roller bracket 39 and turning the bar 27 to disengage its foot 37 from the presser plate 32. The crankshaft 18 is shifted to the right (Fig. 3) and the clothes-cylinder 7 brought to an upright position, the doors 13 each slid outwardly, and the lid 14 removed by pressing the catches 15 outwardly. The clothes to be washed are then placed in the clothes-cylinder 7, and water placed in the housing 6 to the approximate water level 44 as indicated in Fig. 1. The usual soap or washing powder is previously mixed in the water, or may be incorporated in the water by further action of the device. The top lid 14 is then returned and pressed into position, the doors 13 closed, and the crankshaft 18 revolved by the crank 22 or the pulley 24, so as to cause the corresponding revolution of the clothes-cylinder 7.

When the clothes are sufficiently cleansed

- by this process, the crankshaft 18 is stopped and slid to the left, as in Fig. 3, the roller bracket 39 raised, the rack-bar 27 inserted and engaged to the presser-plate 32, and the 5 roller-bracket 39 then dropped into position against the rack-bar 27. The crank shaft 18 is then revolved anti-clockwise so as to lift the rack-bar 27 by means of the gear 26, thereby lifting the presser-plate 32, and 10 in turn, the clothes rack 33 with the clothes resting thereon and pressing the clothes against the top lid 14, until, as the rack-bar continues travelling upward, the presser-plate 32 presses the clothes so tightly against 15 the lid 14 as to overcome the hold of the spring catches 15 with the result that the lid 14 is forced upwardly against the under side of the doors 13 and the clothes are further thereon pressed by the continued 20 travel of the rack-bar 27 and presser plate 32 until sufficient pressure is exerted on the clothes to squeeze out the desired amount of water, at which point the dog 43 is dropped onto the dog wheel 28 to prevent downward 25 travel of the rack-bar 27 when the power is removed from turning the crankshaft 18. The clothes are so held above the water line 44 in the housing, and the doors 13 may then be slid out without damage to the clothes as 30 the lid 14 bears between the clothes and the under sides of the doors, whereupon the clothes are immediately accessible by removing the lid 14. The clothes-rack 33 is provided for the purpose of holding the clothes 35 up and away from the presser-plate 32 so that any clothes possibly entering the narrow slot-like opening between the guide-bars 12 will not be caught by the rack-bar foot 37 as it is inserted in the presser-plate 32.
- 40 By using the clothes-cylinder or receptacle shown in Fig. 8 as being constructed of annular rods, a wash board effect is obtained as the clothes tumble and fall from one end of the receptacle to the other and the water 45 in the housing is effectively forced through the clothes as the receptacle is revolved.
- Having fully described my invention in the form now best known to me, I desire to set out that it is obviously capable of assuming various structural forms as placing the gears driving the clothes-cylinder within the housing, using a worm gear to raise the rack-bar, and other modifications, without departing from the spirit of the invention, and 50 what I claim as new and desire to secure by United States Letters Patent is:
1. In a washing machine, a housing, a clothes receptacle mounted within the housing, said receptacle having a fixed bottom 55 and a detachable top, a guide centrally mounted within and secured to the bottom of said receptacle, a presser plate slidingly carried on said guide, and detachable means of drawing said presser plate upwardly 60 along said guide.
2. In a washing machine, a housing, a clothes receptacle carried within the housing, said receptacle having a fixed bottom and a detachable top, a guide centrally mounted within and secured to the bottom of said receptacle, a presser plate slidingly carried on said guide, a clothes rack slidingly fitted around said guide, a plurality of clothes rack rests secured to the walls of said receptacle, said rests normally holding said rack at a substantial distance above said presser plate when said plate is in its lowest position on said guide, and detachable means of raising said presser plate and said rack 65 upwardly along said guide.
3. In a washing machine, a water retaining housing, a clothes receptacle mounted within said housing, said receptacle having a fixed bottom and a detachable top, a guide within said receptacle, a presser plate slidingly carried by said guide, a clothes rack slidingly carried by said guide, a plurality of clothes rack rests secured to the walls of said receptacle, said rests normally holding said rack at a substantial distance above 70 said presser plate when said plate is in its lowest position, a rack-bar slidingly and detachably retained by said guide, means permitting the engagement and disengagement of said rack-bar with said presser plate, a gear mounted on said housing adapted to mesh with said rack-bar, and locking means to prevent the dropping of said rack-bar when in a raised position.
4. In a washing machine, a water retaining housing, a clothes receptacle within said housing, a detachable lid on said receptacle, a guide secured within said receptacle, a presser plate slidingly carried by said guide and provided with a slot, a presser plate lift bar adapted to be directed by said guide to said slot in said presser plate, a foot on said lift bar adapted to be inserted through the slot in said presser plate and retained therebelow by turning said lift bar on its axis to place said foot crosswise of the slot, a drive shaft mounted on said housing, gear means on said driveshaft adapted to engage selectively said lift bar, a dog wheel mounted, 100 on said driveshaft, and a dog removably 105 engaging with said wheel to prevent the dropping back of said lift bar.
5. In a washing machine, a water retaining housing, a clothes receptacle within said housing, a removable door in said housing, a guide secured in said receptacle, a removable bar adapted to be aligned by said guide, a presser plate slidingly directed by said guide and adapted to be engaged by said bar, a driveshaft mounted on said housing, gear means carried by said driveshaft adapted to be removably engaged with said bar whereby said presser plate may be raised by said lift bar by operating said driveshaft for 110 the purpose of compressing clothes in said 115
6. In a washing machine, a water retaining housing, a clothes receptacle within said housing, a removable door in said housing, a guide secured in said receptacle, a removable bar adapted to be aligned by said guide, a presser plate slidingly directed by said guide and adapted to be engaged by said bar, a driveshaft mounted on said housing, gear means carried by said driveshaft adapted to be removably engaged with said bar whereby said presser plate may be raised by said lift bar by operating said driveshaft for 120 the purpose of compressing clothes in said 125
7. In a washing machine, a water retaining housing, a clothes receptacle within said housing, a removable door in said housing, a guide secured in said receptacle, a removable bar adapted to be aligned by said guide, a presser plate slidingly directed by said guide and adapted to be engaged by said bar, a driveshaft mounted on said housing, gear means carried by said driveshaft adapted to be removably engaged with said bar whereby said presser plate may be raised by said lift bar by operating said driveshaft for 130 the purpose of compressing clothes in said

receptacle against said removable door, and means for holding said bar at any desired elevation.

6. In a washing machine, a water retaining housing, a clothes receptacle within said housing, a driveshaft carried on said housing, a detachable lid on said receptacle, catches holding said lid on said receptacle, a removable door in said housing, a presser plate fitting within said receptacle, lifting means cooperating with said presser plate, said lifting means also engaging with said driveshaft whereby said presser plate may be raised by applying power to said driveshaft, 15 the continued raising of said presser plate causing sufficient pressure to be exerted on said detachable lid to overcome the hold of said catches whereby the catches release said lid and permit it to be pressed against said door, and removable locking means to prevent the dropping back of said presser plate upon removal of power from the driveshaft.

7. In a washer and drier, a housing, removable doors in said housing, a guide secured in said housing, a bar adapted to be aligned by said guide, a presser plate slid- 25 ingly engaging with said guide and adapted to be detachably secured to said bar, a driveshaft mounted on said housing, gear means carried by said driveshaft adapted to be removably engaged with said bar for the purpose of raising said bar and said presser plate to compress clothes between said presser plate and said removable doors, means 30

cooperating with said driveshaft to hold said 35 bar at any desired elevation, and removable bar retaining means whereby said bar is held in engagement with said driveshaft gear means, said removable bar retaining means being adapted to release said bar to permit 40 lateral and rotative movement of said bar.

8. In a washer and drier, a housing, removable doors in said housing, a guide secured in said housing, a bar adapted to be aligned by said guide, a presser plate slid- 45 ingly engaging with said guide and adapted to be detachably secured to said bar, a driveshaft mounted on said housing, gear means carried by said driveshaft adapted to be removably engaged with said bar for the purpose of raising said bar and said presser plate to compress clothes between said presser plate and said removable doors, means 50 cooperating with said driveshaft to hold said bar at any desired elevation, a guide 55 shaft, a roller bracket hinged by one end to said guide shaft straddling said bar and hooking by its other end over said driveshaft, and a roller carried by said roller bracket adapted to contact said bar and hold it in engagement with said driveshaft gear means, the axis of said roller being below the line between the axes of the guide shaft and the driveshaft.

Signed at Indianapolis, county of Marion, 65 State of Indiana, this the 26th day of June, 1924.

WILLIAM O. KIDWELL.
